US00D608724S

(12) **United States Design Patent**
Weber et al.

(10) **Patent No.:** US D608,724 S
(45) **Date of Patent:** ** Jan. 26, 2010

(54) **BICYCLE TIRE TREAD**

(75) Inventors: **Michael Joseph Weber**, Sun Prairie, WI (US); **Michael Hammond**, Madison, WI (US)

JP 55091407 A 7/1980

(73) Assignee: **Trek Bicycle Corporation**, Waterloo, WI (US)

(Continued)

(**) Term: **14 Years**

(21) Appl. No.: **29/333,834**

(22) Filed: **Mar. 16, 2009**

(51) **LOC (9) Cl.** 12-15

(52) **U.S. Cl.** D12/536

(58) **Field of Classification Search** D12/507, D12/511, 512, 536, 539, 542-543, 544, 571, D12/577-579; 152/209.1, 209.8-209.13, 152/209.28, 455

See application file for complete search history.

(57) **CLAIM**

The ornamental design for a bicycle tire tread, substantially as shown and described.

DESCRIPTION

FIG. 1 is an isometric view of a bicycle tire tread according to the present invention;

FIG. 2 is a top plan view of the bicycle tire tread of FIG. 1; FIG. 3 is a side elevation view of the bicycle tire tread of FIG. 1;

FIG. 4 is a front elevation view of the bicycle tire tread of FIG. 1;

FIG. 5 is a rear elevation view of the bicycle tire tread of FIG. 1; and,

FIG. 6 is a partial top plan view of the bicycle tire tread of FIG. 1 detailing three lugs thereof.

The broken line showing of the tire is included for the purpose of illustrating environment and forms no part of the claimed design.

1 Claim, 3 Drawing Sheets
